UNITED STATES PATENT OFFICE.

CYRUS B. THAYER, OF BOSTON, MASSACHUSETTS, ASSIGNOR TO HIMSELF, AND CHAS. ROBINSON, OF CAMBRIDGEPORT, MASSACHUSETTS.

INSTRUMENT FOR TURNING THE LEAVES OF MUSIC-BOOKS. &c.

Specification of Letters Patent No. 22,690, dated January 18, 1859.

To all whom it may concern:

Be it known that I, CYRUS B. THAYER, of Boston, in the county of Suffolk and State of Massachusetts, have invented a new and Improved Music-Leaf Holder and Turner; and I do hereby declare that the following is a full and exact description thereof, reference being had to the accompanying drawings, making part of this specification.—Fig. 1 being a front elevation of the instrument; Fig. 2, a plan thereof; Fig. 3, a similar view thereof, with a portion of the base removed to show the interior arrangement; Fig. 4, a cross-section thereof in the plane indicated by the line $x\ x$, Fig. 1.

Like letters designate corresponding parts in all the figures.

My improvement may be made as a portable instrument applicable to the music-desk of any piano, organ, melodeon or other similar musical instrument; or it may be made as a part of the music-desk, or rack, itself.

A base A, is provided, to the rear of which is secured a back B, which may be in the form of an upright or slightly leaning standard, since the usual music-rack will assist in sustaining the music-leaves. This back is of sufficient height to reach above the music-leaves, when they are placed against it. Clamp-jaws C, D, are secured in front of the back B, one being immovable and the other movable to and from its companion, toward which it is moved and tightened by an eccentric button I, and from which it is automatically separated by elastic cords α , α , (Fig. 4,) passing through said clamp-jaw and the back B, or by any equivalent means.

In the top of the back B, is a slot, or notch, b , for the reception of small cords E, E. These cords may be of catgut or other suitable material. They are arranged in pairs, and to the upper end of each pair is secured a small knob e, for holding said cords in the notch b , which thus becomes the center of motion for said cords, as hereinafter set forth. To the lower end of each pair of cords is secured a ring, or thimble, d , which slides on a curved rod or way, F. This rod is nearly or quite a half a circle in extent, and is concentric with the notch b , where the upper ends of the cords E, E, are attached, so that when said cords are carried around (as presently to be de-

scribed,) they may be kept straight, and the leaves which they turn may not be rubbed or worn. Elastic cords G, G, are secured to the thimbles d , d , whence they are passed around small pulleys h , h , (Figs. 1 and 3,) situated at the left hand end of the base A, and extend thence around similar pulleys s , s , s , situated in the right-hand end of the base, and finally toward the left again, to a point i , of attachment. The cords, thus extend alternately to the right and left, a sufficient number of times, to take up their whole length. When thus arranged the elastic cords have a free movement which allows them to stretch or contract, without much friction. The number of pairs of cords E, E, thimbles d , d , and elastic cords G, G, should be sufficient to receive as many leaves of music at once as may be found in any one piece to be played.

Instead of the elastic cords G, G, any equivalent may be used which will accomplish a like result; as, for instance, inelastic cords winding around drums inclosing coiled springs, similar to the drum inclosing the mainspring of a watch.

At the right-hand end of the base A, is situated an escapement catch II, secured to a horizontal axis l , which turns in a suitable bearing in said base. This catch has two points o , and p , extending inward so as to receive the rod, or way, F, between them, as shown most clearly in Fig. 1; but not too far to prevent their being disengaged from the embrace of the rod by a slight pressure downward. The two points are not situated in the same perpendicular plane, but in planes sufficiently separated to receive one of the thimbles d , between them; so that, when the upper or front point p , rests against the front side of one thimble, the lower, or rear point o , will be between the front thimble and the next succeeding thimble. And the points are also situated vertically apart not sufficiently to allow the escape of a thimble between them, till they are raised somewhat by the hand of the player. The upper point p , is pressed and held down in contact with the rod F (as shown in Fig. 1), by a spring m , acting on the end l , of the axis h ; or by any equivalent means. The escapement-catch is actuated by means of an arm n , which is touched by the player.

The action of the instrument is as fol-

lows: If the leaves to be turned are those of a book, the book is merely placed against the back B; but if the leaves are those of sheet-music, the backs of the leaves are placed between the clamp-jaws C, D, and secured therein by means of the eccentric I. Each leaf to be turned, in the performance of a piece, is then placed respectively between a pair of the cords E, E, and the upper ends of said cords are all placed in the notch b, at the top of the back. When they are thus arranged, the escapement-catch H, is unsprung from the rod F, by pressing it downward with the hand. Then the thimbles d, d, are, all together, brought around from the left-hand end of the base, to the opposite end, and the escapement-catch again made to stride the rod, thereby holding the cords and the music-leaves at the right-hand of the instrument. Then, at the moment of completing one page of the music by merely slightly touching the end of the arm n, so as to move it inward, (which can be done in a moment, and without scarcely interfering with the performance of a piece,) the upper point p, of the catch, is freed from the front thimble, which immediately escapes; when the cord G, carries it instantly around to the left of the instrument, bearing the leaf with it. At the same time that the upper point of the escapement catch is rising, to free the front thimble, the

lower point thereof rises in front of the succeeding thimble, and holds it till the spring m forces back the front point so as to receive the thimble as before, and ready for setting free the second leaf; and so on till all are set free. In this manner, any number of leaves may be turned, one by one, by simply touching the arm n.

What I claim as my invention and desire to secure by Letters Patent, is—

1. The double holding cords E, E, E, elastic springing cords G, G, G, or their equivalents, back B, provided with clamps C, D, and notch or catch b, and the curved, concentric rod, or way, F, arranged and operating in connection with and in relation to each other substantially in the manner and for the purpose herein specified. 50

2. I also claim the escapement-catch H, constructed, arranged and operating in connection with the curved rod F, and thimbles of the holding cords E, E, E, substantially 55 as described.

In witness that the above is a true specification of my improved instrument for turning music leaves and book leaves, I hereunto set my hand this third day of December, 1858.

CYRUS B. THAYER.
